UNITED STATES PATENT OFFICE.

CHARLES W. MUELLER, OF ST. LOUIS, MISSOURI, ASSIGNOR TO LEWIS INVISIBLE STITCH MACHINE CO., OF ST. LOUIS, MISSOURI, A CORPORATION OF MAINE.

PLUNGER-OPERATING MECHANISM FOR BLINDSTITCH SEWING MACHINES.

Application filed October 21, 1924. Serial No. 744,983.

This invention relates to new and useful improvements in blind stitch sewing machines generally, although more particularly to the plunger mechanism thereof.

In blind stitch sewing machines employed for felling operations, the needle is generally oscillated in a plane at a slight angle to the line of feed to the superimposed fabric or fell during each reciprocation. A vertically reciprocating plunger functions to project a node of the body fabric into the path of the needle in advance of alternate oscillations of the needle whereby the latter will on said alternate oscillations engage both the body fabric and the fell. In felling the bottoms of trousers and other tubular articles, it is desirable to employ a machine having a lower arm around which the tubular work may be positioned and to employ readily accessible means for adjusting vertically the bodily position of oscillation of the plunger in order to predetermine the depth of the needle penetration in the material. It is also desirable to provide means for yieldably supporting the plunger whereby the same will during its upward or work positioning movement, become automatically relieved upon the passage under the presser foot of seams or other thick portions of the article being felled.

One of the principal objects of my invention is, therefore, to provide a blind stitch sewing machine including a standard provided with a tubular work arm of relatively small diameter and having a plunger operating at the free end thereof with driving connections extending along the arm to the standard, and means located at a point remote from the free end of the arm and beyond the work being felled for adjusting the plunger mechanism either while the machine is running or while it is idle, to predetermine the high point of oscillation thereof and the resultant depth of needle penetration in the fabric.

Another important object of the invention is to provide means for yieldably supporting the plunger whereby the latter, upon the passage of seams or other thick portions of fabric, will become automatically relieved, thus maintaining a uniform depth of needle penetration in the fabric and also avoiding the choking of the machine and the damaging of the material.

A further object of the invention is to provide an oscillatory plunger lever and a fulcrum lever with an operating connection therebetween, and means for adjusting the angular position of the fulcrum lever to vary the vertical position of bodily oscillation of the plunger lever to predetermine the depth of needle penetration in the fabric being felled.

With the above and other objects in view which will more readily appear as the nature of the invention is better understood, the same consists in the novel construction, combination and arrangement of parts hereinafter more fully described, illustrated and claimed.

In the accompanying drawings which illustrate one form of my invention as being applied to a "Lewis" type of blind stitch sewing machine,

Figure 1 is a front elevation of such a sewing machine, parts thereof being shown in section,

Figure 2 is an end view of the lower work arm,

Figure 3 is a bottom plan view showing the mechanism contained in the lower arm and standard,

Figure 4 is a vertical sectional view taken through the standard,

Figure 5 is an enlarged sectional view of the plunger and its operating mechanism,

Figure 6 is a sectional view taken on the line 6—6 of Figure 5, and

Figure 7 is a sectional view taken on the line 7—7 of Figure 5.

Like reference numerals designate corresponding parts throughout the several figures of the drawings.

Although my invention is especially applicable to blind stitch sewing machines of the "Lewis" type and I have so illustrated the same, it will be apparent that my invention is capable of use in connection with other types of machines.

In the drawings, the sewing machine comprises a supporting standard 5 having upper and lower arms 6 and 7 connected thereto. A stitching head 8 which is disposed above the free end of the lower arm 7 is supported from the free end of the upper arm 6. This stitching head includes a needle mechanism which forms the subject matter of my co-pending application filed October 21, 1924, Ser. No. 744,984. The stitching head in-

cludes a stationary presser foot 9 having the usual work receiving opening formed therein, a needle 11 which oscillates across the usual opening in a plane preferably at a slight angle to the line of feed and which is also given a lateral or shogging movement, and a complementary stitch forming mechanism such as a rotary hook 12, the needle and hook being actuated from a main driving shaft 13 journaled in the upper arm 6. It is believed that further description of the stitching will be unnecessary as it, per se, forms no part of the present invention.

Cooperating with the under face of the stationary presser foot is a feed dog 14 for intermittently feeding the fabric passed the stitch forming mechanism, and a work clamp 15 which intermittently clamps the work against the foot when the feed dog is idle whereby the work will be retained against movement while the needle 11 enters and remains in the work, the clamp being released and the feed dog functioning while the needle is out of the work.

The feed dog 14 is of the 4-motion type, that is, forward and backward and up and down movements are imparted thereto.

The backward and forward movement of the feed dog is obtained through the medium of a rock shaft 16 which I term the feed travel shaft and the up and down movement of the feed dog is obtained from a rock shaft 17 which I term the feed lift shaft. These rock shafts 16 and 17 extend longitudinally within the lower arm 7 and have their right hand ends journaled in bearings formed in a depending lug 18 and their left hand ends journaled in bearings formed in a block 19 located at the left hand end of the lower arm 7 and formed integral therewith. Fixed to the outer end of the feed travel shaft 16 is a rock arm 20 and pivotally connecting the outer end of this rock arm and the forward extremity of the feed dog 14 is a link 21. The rock arm 20 extends in a general horizontal direction. Thus upon movement of the rock arm 20 the link 21 will impart backward and forward movements to the feed dog 14. The feed dog 14 is pivotally connected as at 22 to the upper end of a substantially vertically disposed link 23, the lower end of said link being pivotally connected as at 24 to the horizontal arm 25 of a bell crank lever 26, the vertical arm 27 of said bell crank lever being pivotally connected as at 28 to one end of a link 29, the other end of said link 29 being pivotally connected as at 30 to the outer end of a vertically disposed rock arm 31 fixed to the feed lift shaft 17. In order to retain the feed surface of the feed dog in a substantially horizontal plane during the feeding movements thereof, I provide a spring 32 which is connected between a pin 33 on the link 23 and a pendent tail 34 fixed to the

feed dog 14. It will, therefore, be observed that upon rocking movement of the feed lift shaft 17 the vertical link 23 will be bodily raised and lowered and consequently the feed dog will be given its upward and downward movements. By proper timing of the shafts 16 and 17 a 4-way feed motion will be imparted to said feed dog.

The bell crank lever 26 is pivoted as at 35 and this pivot is fixed to a head 36 secured to the lower end of a guide post 37, said head and post forming a vertically movable carrier. The post 37 is mounted for vertical sliding movements in a bore formed in the block 19, and this block is formed with a seat 38 for receiving and limiting the upward movement of the carrier. This carrier is normally held in its highest position by means of a flat spring 39, the inner end of which is rigidly secured to the arm 7 and the outer end thereof is disposed to the carrier so as to yieldably hold the latter in its highest position. The upper end of the post 37 carries a pair of rearwardly projecting arms 40—40 between which is pivoted as at 41 the work clamp 15.

From the foregoing it will be observed that when the feed dog 14 is elevated to its highest position, the fulcrum 35 of the bell crank lever 26 is then shifted to the pivot 24, and consequently the last part of the rocking movement of the crank arm 31 will cause the bell crank lever 26 to be moved downwardly about its fulcrum 24 thus lowering the work clamp 15. The parts are so timed that the work clamp is lowered prior to the feeding movement of the feed dog. The reverse order of movement will take place at substantially the time when the feed dog reaches the end of its feeding stroke, thus causing the clamp to engage the fabric and clamp the latter against the presser foot 9 prior to the time the feed dog begins its downward movement.

In order to rock the feed travel shaft 16 and the feed lift shaft 17 I have provided a main shaft 13 with eccentrics 42 and 43 respectively. A connection rod 44 has its upper end engageable with the eccentric 42 and has its lower end pivotally connected as at 45 to a rock arm 46 fixed to said shaft 16. A connection rod 47 has its upper end engageable with the eccentric 43 and has its lower end pivotally connected with a rock arm 49 fixed to the shaft 17. It will be noted that the connection rods 44 and 47 are disposed within the post or standard 5 of the frame.

As previously stated, the work as it is fed past the stitching head 8, is adapted to be intermittently crimped or bent so as to form a node which will be positioned in the path of the needle whereby the latter will enter said node and project a penetrant needle thread loop therethrough. In order

to bring about this crimping operation, I have provided a plunger 50 which is located within the arm 7 and is actuated from the main shaft 13 by a mechanism so as to project said plunger upwardly in advance of alternate needle reciprocations. This plunger 50 consists of an elongated arm 51 which extends lengthwise within the arm 7 of the machine frame and is pivoted at its inner end as at 52 to a lug 53 depending from the upper part of said arm 7. The arm 51 of the plunger extends in a general horizontal direction and the outer end portion 54 thereof extends upwardly at substantially right angles to the arm 51 and constitutes the plunger proper. The plunger 50 is oscillated about its fulcrum 52 through the medium of a toggle connection consisting of a link 55 and a link 56. These links extend below the plunger 50 and the upper end of the link 55 is pivotally connected as at 57 to the plunger. The two links 55 and 56 are pivotally connected as at 58. The lower end of the link 56 is pivotally connected as at 59 to a fulcrum lever 60 which extends longitudinally of the arm 7. The fulcrum lever 60 is, of course, disposed under the plunger 50 and is fulcrumed at its outer end as at 61 to the block 19. The inner end of the fulcrum lever 60 is limited in its upward movement by means of a depending stop 62 fixed to the arm 7. A coil spring 63 has its upper end connected to the arm 7 and its lower end to the fulcrum lever 60. Thus the fulcrum lever is normally held in yieldable contact with the stop 62. In order to positively adjust the position of the fulcrum lever 60 relative to the stop 67 I have provided the lever 60 with an adjusting screw 64 which cooperates with said stop. This screw 64 is provided with a head having a knurled edge and a spring latch 65 cooperates with said knurled edge to retain the screw in an adjusted position.

In order to oscillate the plunger 50 through the medium of the toggle links 55 and 56, I have journaled in the standard 5 a rotary shaft 66 which is driven from the main shaft 13 by a one-to-two gear coupling 67 whereby said shaft 66 will be rotated once during every two revolutions of the main shaft. Fixed to the lower end of the shaft 66 is a cam 68, the under surface thereof being formed with a cam groove 69. Located in this cam groove 69 is a roller 70 which is carried by one end of the bell crank lever 71 said bell crank lever being fulcrumed as at 72 upon the standard 5. The other arm of the bell crank lever is pivotally connected as at 73 to the inner end of a connection rod 74 which extends lengthwise of the arm 7 and has its outer end pivotally connected as at 75 to the link 56 of said toggle.

From the foregoing it will be observed that because of the two-to-one coupling 67 the plunger 50 will be oscillated during every other reciprocation of the needle. The parts are so timed that the plunger will be elevated prior to the penetrating stroke of the needle so as to project a node of fabric into the path of said needle and by means of the cam 68 the plunger will be retained in its elevated position during the entire time the needle is in the node of material. In order to predetermine the depth of needle penetration in said node, the fulcrum lever 60 may be adjusted by the screw 64. Thus by lowering the fulcrum lever 60 the vertical bodily position of oscillation of the plunger will be correspondingly lowered and, therefore, the depth of needle penetration in the material will be decreased. Should it be desirable to increase the depth of needle penetration in the material the fulcrum lever 60 is raised by releasing the adjusting screw 64, the spring 63 causing the lever to remain either in direct contact with the stop 62 or in contact with said stop through the medium of the screw. When seams or other thick portions of material are fed past the stitching head the same depth of needle penetration will be maintained owing to the fact that the plunger during its upward travel will meet the resistance of the fabric, due to the presser foot being fixed, and consequently the upward movement of the plunger will be limited. This limitation of the upward movement is compensated for by reason of the fulcrum lever 60 being yieldably supported by the spring 63 and consequently when the resistance of the material is thus met by the plunger, the movement of the toggle will be continued to its maximum extent thus forcing down the fulcrum lever 60 against the tension of the spring 63. The adjusting screw 64 is located at a point remote from the line of feed and consequently access may be readily had to this adjusting screw while tubular work is being stitched.

I claim:

1. In a blind stitch sewing machine, the combination with a frame including a standard, an upper arm and a lower tubular arm, of a stitching head carried by the upper arm, a presser foot fixed to the stitching head and formed with a work receiving opening, an oscillatory plunger lever extending lengthwise within said lower arm and having its inner end pivoted thereto, the free end of the plunger lever being movable into and out of the opening in the presser foot, means for oscillating the plunger lever, and means located between the presser foot and the standard for adjusting vertically the bodily position of oscillation of said plunger lever, said adjust-

ing means being accessible from the underside of the lower arm.

2. In a blind stitch sewing machine, the combination with a frame including a standard and upper and lower arms, of a stitching head carried by the upper arm, a presser foot fixed to the stitching head and formed with a work receiving opening, an oscillatory plunger lever extending lengthwise within said lower arm and having its inner end pivoted thereto, the free end of the plunger lever being movable into and out of the opening in the presser foot, a fulcrum lever extending lengthwise of said lower arm below the plunger lever and having one end pivoted to said lower arm, means for oscillating said plunger lever including a toggle connection between said plunger lever and said fulcrum lever, and means cooperating with said fulcrum lever for adjusting vertically the bodily position of oscillation of said plunger lever.

3. In a blind stitch sewing machine, the combination with a frame including a standard and upper and lower arms, of a stitching head carried by the upper arm, a presser foot fixed to the stitching head and formed with a work receiving opening, an oscillatory plunger lever extending lengthwise within said lower arm and having its inner end pivoted thereto, the free end of the plunger lever being movable into and out of the opening in the presser foot, a fulcrum lever extending lengthwise of said lower arm below the plunger lever and having its outer end pivoted to said lower arm, means for oscillating said plunger lever including a toggle connection between said plunger lever and said fulcrum lever, and means cooperating with the inner end of said fulcrum lever for adjusting vertically the bodily position of oscillation of said plunger lever.

4. In a blind stitch sewing machine, the combination with a frame including a standard and upper and lower arms, of a stitching head carried by the upper arm, a presser foot fixed to the stitching head and formed with a work receiving opening, an oscillatory plunger lever extending lengthwise within said lower arm and having its inner end pivoted thereto, the free end of the plunger lever being movable into and out of the opening in the presser foot, a fulcrum lever extending lengthwise of said lower arm below the plunger lever and having its outer end pivoted to said arm, means for oscillating said plunger lever including a toggle connection between said plunger lever and said fulcrum lever, a stop fixed to the lower arm and cooperating with the inner end of the fulcrum lever to limit the upward movement thereof, a spring connecting said lower arm and said fulcrum lever to yieldably hold the latter in engage-

ment with said stop, and an adjusting screw carried by the fulcrum lever and engageable with said stop for varying the angular position of the fulcrum lever whereby the bodily position of oscillation of the fulcrum lever will be adjusted vertically.

5. In a blind stitch sewing machine, the combination with a frame including a standard and upper and lower arms, of a stitching head carried by the upper arm, a presser foot fixed to the stitching head and formed with a work receiving opening, an oscillatory plunger lever extending lengthwise within said lower arm and having its inner end pivoted thereto, the free end of the plunger lever being movable into and out of the opening in the presser foot, a fulcrum lever extending lengthwise of said lower arm below the plunger lever and having one end pivoted to said lower arm, a toggle connection between said plunger lever and said fulcrum lever, a rotary main shaft journaled in the upper arm of the frame, a vertically disposed cam shaft journaled in said standard and operatively connected with said main shaft, a cam fixed to the lower end of said cam shaft, a link connection extending lengthwise of the lower arm between said toggle and said cam, and means cooperating with said fulcrum lever for adjusting vertically the bodily position of oscillation of said plunger lever.

6. In a blind stitch sewing machine, the combination with a frame including a standard and upper and lower arms, of a stitching head carried by the upper arm, a presser foot fixed to the stitching head and formed with a work receiving opening, an oscillatory plunger lever extending lengthwise within said lower arm and having its inner end pivoted thereto, the free end of the plunger lever being movable into and out of the opening in the presser foot, a fulcrum lever extending lengthwise of said lower arm below the plunger lever and having one end pivoted to said lower arm, a toggle connection between said plunger lever and said fulcrum lever, and a cam controlled means connected to said toggle for oscillating said plunger lever.

7. In a blind stitch sewing machine the combination with a frame including a standard and upper and lower arms, of a stitching head carried by the upper arm, a presser foot fixed to the stitching head and formed with a work receiving opening, an oscillatory plunger lever extending lengthwise within said lower arm and having its inner end pivoted thereto, the free end of the plunger lever being movable into and out of the opening in the presser foot, a fulcrum lever extending lengthwise of said lower arm below the plunger lever and having its outer end pivoted to said arm, a stop fixed to the lower arm and cooperating with

the inner end of the fulcrum lever to limit the upward movement thereof, a spring connecting said lower arm and said fulcrum lever to yieldably hold the latter in engagement with said stop, a toggle connection between said plunger lever and said fulcrum lever, a cam controlled means connected to said toggle connection for oscillating said plunger lever, and an adjusting screw carried by the fulcrum lever and engageable with said stop for varying the angular position of the fulcrum lever whereby the bodily position of oscillation of the fulcrum lever will be adjusted vertically.

8. In a blind stitch sewing machine the combination with a frame including a standard and upper and lower arms, of a stitching head carried by the upper arm, a presser foot fixed to the stitching head and formed with a work receiving opening, an oscillatory plunger lever extending lengthwise within said lower arm and having its inner end pivoted thereto, the free end of the plunger lever being movable into and out of the opening in the presser foot, a fulcrum lever extending lengthwise of said lower arm below the plunger lever and having its outer end pivoted to said arm, a stop fixed to the lower arm and cooperating with the inner end of the fulcrum lever to limit the upward movement thereof, a spring connecting said lower arm and said fulcrum lever to yieldably hold the latter in engagement with said stop, a toggle connection between said plunger lever and said fulcrum lever, a rotary main shaft journaled in the upper arm of the frame, a vertically disposed cam shaft journaled in said standard and operatively connected with said main shaft, a cam fixed to the lower end of said cam shaft, a driving connection between said cam and said toggle for oscillating said

plunger lever including a link extending lengthwise of the lower arm, and means cooperating with said fulcrum lever for adjusting vertically the bodily position of oscillation of said plunger lever.

9. In a blind stitch sewing machine, the combination with a presser foot having a work opening, of a plunger lever fulcrumed below said presser foot and having its free end movable into and out of the work opening of said presser foot, a fulcrum lever mounted below said plunger lever, a stop to limit the upward movement of said fulcrum lever, a toggle connection between said plunger lever and said fulcrum lever, means for actuating said toggle connection to oscillate said plunger lever into and out of the work opening of said presser foot, and a spring for normally holding said fulcrum lever in engagement with said stop.

10. In a blind stitch sewing machine, the combination with a presser foot having a work opening, of a plunger lever fulcrumed below said presser foot and having its free end movable into and out of the work opening of said presser foot, a fulcrum lever mounted below said plunger lever, a stop to limit the upward movement of said fulcrum lever, a toggle connection between said plunger lever and said fulcrum lever, means for actuating said toggle connection to oscillate said plunger lever into and out of the work opening of said presser foot, a spring for normally holding said fulcrum lever in engagement with said stop, and means cooperating with said fulcrum lever and stop for varying the bodily position of said lever to adjust the high point of oscillation of said plunger lever.

In testimony whereof I hereunto affix my signature.

CHARLES W. MUELLER.
